(57) **CLAIM**

The ornamental design for a detector for detecting the angular position of a rotatable shaft, as shown and described.

DESCRIPTION

FIG. 1 is a top perspective view of a detector for detecting the angular position of a rotatable shaft showing our new design;

FIG. 2 is a top plan view thereof;

FIG. 3 is a bottom plan view thereof;

FIG. 4 is a front view thereof;

FIG. 5 is a rear view thereof;

FIG. 6 is a right view thereof; and,

FIG. 7 is a left view thereof.
